DESIGN FOR A BOTTLE

James S. Steelman, Millville, N. J., assignor to
Whitall Tatum Company, New York, N. Y., a
corporation of New Jersey

Application August 22, 1934, Serial No. 53,013

Term of patent 7 years

To all whom it may concern:

Be it known that I, JAMES S. STEELMAN, a citizen of the United States, residing at Millville, Cumberland County, New Jersey, have invented a new, original, and ornamental Design for a Bottle, of which the following is a specification, reference being had to the accompanying drawing, forming part thereof.

Figure 1 is a front view;

Figure 2 is a side view;

Figure 3 is a top view of a bottle showing my new design, wherein the lower left hand corner is partially broken away and sectioned to illustrate the contour of the corner flutings.

I claim:

The ornamental design for a bottle as shown and described.

JAMES S. STEELMAN.
